TOOL FOR INSTALLING A SNOW GUARD ON
A SHINGLED ROOF

Joseph D. Zaleski, 100 S. Mountain Drive,
New Britain, Conn.

Filed Apr. 9, 1963, Ser. No. 74,369

Term of patent 14 years

(Cl. D54—13)

FIG. 1

FIG. 2

FIG. 3

FIG. 1 is a plan view of a tool for installing a snow guard on a shingled roof, showing my new design.

FIG. 2 is a side view of the same.

FIG. 3 is an end view of the same.

I claim:

The ornamental design for a tool for installing a snow guard on a shingled roof, as shown.
